UNITED STATES PATENT OFFICE.

OLIVER A. ALEXANDER, OF PHILADELPHIA, PENNSYLVANIA.

TRIPLE VALVE FOR AIR-BRAKES.

SPECIFICATION forming part of Letters Patent No. 794,835, dated July 18, 1905.

Application filed April 23, 1904. Serial No. 204,556.

To all whom it may concern:

Be it known that I, OLIVER A. ALEXANDER, a citizen of the United States, residing at Philadelphia, in the county of Philadelphia and 5 State of Pennsylvania, have invented a certain new and useful Improvement in Triple Valves for Air-Brakes, of which the following is a full, clear, and exact description.

This invention has for its object to produce 10 a simple single-element triple valve for air-brake apparatus, whereby both service and emergency stops may be readily effected without the use of slide-valves and special emergency valves or pistons.

15 The invention consists of a suitably-ported valve-shell adapted to be connected to the auxiliary reservoir and train pipe and having a single piston provided with ported laps coöperating with the ports in the shell, so as to 20 actuate the brake-cylinder to apply the brakes in both service and emergency stops and to release them, and serving thus without the interposition of other valves, pistons, or equivalent valve-like mediums between it and 25 the engineer's valve.

In the accompanying drawings, illustrating 30 the invention, in the several figures of which like parts are similarly designated, Figure 1 is a view, partly in section and partly in elevation, showing the valve applied to a standard freight-car air-brake apparatus. Fig. 2 is a longitudinal section of the triple valve. Fig. 3 is an elevation of the gasket. Fig. 4 is a bottom plan view of the piston. Fig. 5 35 is an elevation of the retaining-ring.

The brake-cylinder 1, with its spring-pressed piston 2, and the auxiliary reservoir 3, with its through-pipe 4 for connecting the triple valve and the brake-cylinder, may be 40 and are here shown as usual.

The triple valve comprises a shell 5, having a train-pipe connection 6 and flange 7, by which it may be bolted to the auxiliary reservoir. In the train-pipe connection is a seat 45 8, and in the retaining-ring 9 at the opposite end is a seat 10 for receiving and guiding the stems 11 and 12 of the piston 13. This retaining-ring maintains constant communication between the triple valve and the auxil-

iary reservoir. An expansion-spring 14 is 50 interposed between seat 8 and the piston. The shell 5 has a bushing 15, in which is cut a leakage-groove 16 next the piston at the point where said piston comes to rest in exhausting the brake-cylinder, so that the train-pipe air may leak past the piston into and fill the auxiliary reservoir, as usual. The piston is made with laps 17 and 18 at front and rear, the former provided with one or more through-ports 19 and the latter provided with an in- 55 closed port 20, made as a recess in its periphery.

21 is a port in the shell, leading from the brake-cylinder to the front of the piston, and 22 is a port in the shell opening into port 21 60 and into the shell in rear of the piston.

23 is the exhaust-port, opening into the external atmosphere.

Ports 19 and 21 coöperate, and ports 20, 22, and 23 coöperate.

70 The triple valve has a leather or other gasket 24 interposed between it and the auxiliary reservoir.

The triple valve is shown in Fig. 2 as in the normal position, train running and air 75 leaking past its piston into the auxiliary reservoir. If the train-pipe pressure be reduced, the piston will be moved to the right, closing the leakage-port and uncovering port 22, so as to permit the air to flow from the auxiliary 80 reservoir through the valve-shell and thence through port 22 into the through-pipe 4, leading from said valve into the brake-cylinder, thereby applying the brakes in accordance 85 with ordinary service-stop usage. If an emergency-stop be required, then the train-pipe pressure is further reduced, and the piston will be moved still farther to the right until its port 19 registers with the port 21, 90 thereby admitting train-pipe pressure also into the air-brake cylinder, in addition to the pressure from the auxiliary reservoir. After an emergency application has been made the spring 14 will move the piston into lap position. Upon restoration of full train-pipe 95 pressure its force, aided by the spring 14, will suffice to move the piston to the left against the auxiliary-reservoir pressure, close ports

21 and 22, and open communication between the brake-cylinder and the exhaust, and so cause the release of the brakes.

It will be seen that this piston-valve performs the functions and takes the place of the piston and slide valve of the plain triple and also of the emergency piston of the quick-action valve.

What I claim is—

- 10 A triple valve, comprising a shell adapted to be connected with an auxiliary reservoir in open communication therewith, and a piston in said shell exposed on one side to train-pipe pressure and on the other side to auxiliary-reservoir pressure, and having front and rear laps on one side only, the front lap having a through-port and the rear lap having an inclosed port, the shell having a front port leading rearwardly to the brake-cylinder and controlled by the through-port lap, and a rear port leading into the front port and an exhaust-port, the rear port and exhaust-port

controlled by the inclosed-port lap, so that upon reduction of train-pipe pressure the piston will be moved and its rear lap will uncover the rear port and admit auxiliary-reservoir pressure to the brake-cylinder, and upon further reduction of train-pipe pressure the piston will be moved farther in the same direction and its front-lap port alined with the front port in the shell and thereby uncover both the rear and front ports in the shell and admit to the brake-cylinder both auxiliary-reservoir and train-pipe pressure, thereby effecting respectively service and emergency stops without the intervention of auxiliary or supplementary valves.

In testimony whereof I have hereunto set my hand this 20th day of April, A. D. 1904.

OLIVER A. ALEXANDER.
